SELF-ADJUSTING BRIDGE FOR VIOLIN INSTRUMENTS

Douglas Jaquith, Salem, Oreg.
(10302 Ilona Ave., Los Angeles, Calif.)
Filed Apr. 27, 1959, Ser. No. 809,096
3 Claims. (Cl. 84—309)

This invention relates to a construction for the bridge of instruments of the viol class that spaces the strings of the instrument away from the instrument body.

This invention has as its principal object the provision of a bridge for such an instrument that may be easily fitted to the instrument, and that once fitted rests firmly on the body of the instrument with tight contact between the bridge and the instrument body.

More specifically, it is an object of the invention to provide a bridge for a viol instrument that has pivoted foot support therefor, the provision of the pivots enabling the feet to move so as to conform themselves to the contour of the instrument body. The particular pivot construction employed enables the use of conventional and established materials in the manufacture of the bridge. The construction also makes possible easy replacement of broken parts.

Other features and objects of the invention will become apparent as the following description is read in conjunction with the accompanying drawings, wherein:

FIG. 1 is a front view of a violin provided with the bridge of this invention;

FIG. 2 is a view, slightly enlarged, of one face of the bridge;

FIG. 3 is a view of one edge of the bridge; and

FIG. 4 is a section view, on an enlarged scale, and taken along the line 4—4 in FIG. 2.

Referring now to the drawings, 10 indicates generally a violin, such instrument being exemplary of instruments of the viol class. The violin comprises body 11, a scroll 12, a peg box 14, a finger board 16 and tailpiece 18. Extending between the tailpiece at one end of the violin and the pegs mounted in the peg board at the other end are the usual violin strings 20. These strings are spaced intermediate their ends from the body of the violin by a bridge indicated generally at 22.

Considering now the construction of bridge 22, and referring now more particularly to FIGS. 2, 3, and 4, the bridge comprises a standard 26 which is a flat-sided piece ordinarily made of maple or other wood and having an arcuate top edge 28 which supports the individual violin strings. At the base in substantially the plane of the standard are a pair of spaced supports 30. These mount the standard on the violin body and space it slightly outwardly therefrom. The standard as is conventional tilts slightly, with its upper edge leaning toward the tailpiece of the violin. Thus, in FIG. 3 the line 31 is perpendicular to the body of the violin, and standard 26 inclines slightly away from this perpendicular.

Each support 30 is provided with an elongated foot portion 32 extending substantially in the plane of the standard. These are thin and have a degree of flexibility. The foot portions have concavely curved bottom surfaces 33 that are slightly over-bowed relative to the curvature of the violin body (see the dotted outline in FIG. 2). When the bridge is mounted on the violin body and pressure exerted thereon, the ends of the foot portions flex outwardly so that the entire length of each fits snugly against the instrument.

A tight, snug fit between the bridge and violin body is further facilitated by mounting the foot portions so that they are pivotable relative to the standard portion of the bridge. This enables each to swing in the direction required to permit the ends and center of the foot portion to

2

come into full contact with the violin body. Thus each foot portion has integral therewith a cylindrically rounded mounting portion 34. This is rounded over an arc of substantially more than half a circle and acts as a journal portion in the pivot construction. Cut into the base edge 27 of standard 26 are rounded cutouts 36. These are more than half round but less than full circle, and are complementary to portions 34. The cutouts snugly encompass portions 34 and function as bearing portions. Rounded mounting portions 34 are inserted into cutout 36 by moving them laterally into a position of alignment. Since each cutout arcs over an angle that is substantially greater than 180 degrees, separation of the pieces cannot occur in directions parallel to the plane of the standard. The rounded portions 34 fit snugly into the cutouts and friction present inhibits lateral separation.

As already noted, the standard tilts slightly toward the tailpiece of the violin. The supports when pivoting to fit the body of a violin should pivot about mutually parallel axes that are parallel to the surface of the violin body. Thus each portion 34 and its complementary cutout is formed to accommodate pivotal movement about an axis such as that indicated at 38 in FIG. 4 that in a vertical plane extends obliquely to the plane of standard 28, the latter being indicated at 40. Axis 38 is the center axis in FIG. 4 of the cylindrically rounded mounting portion 34 shown.

Using the bridge construction described, it is an easy matter to mount a bridge firmly on the body of a violin with the supports therefor engaging snugly and throughout their length the top of the violin. This is produced without the necessity of having to shape each bridge to each violin. The rounded portions 34 of the foot portions provide an enlarged pivot for the foot portions of considerable strength. The bridge may be made entirely of wood, and a broken foot support is easily replaced.

It is claimed and desired to secure by Letters Patent:

1. For a viol instrument, a bridge comprising an upright standard, and supports at the base of the standard occupying substantially the plane of the standard for supporting the standard over the body of such instrument, said supports including elongated feet with concave bottom surfaces and having resilient and flexible ends, said bottom surfaces being over-bowed relative to the curvature of the body of the instrument, and pivot means connecting said supports to the standard, the flexibility of the feet enabling them to yield when the bridge is mounted on an instrument so that their bottom surfaces have a curvature conforming to the curvature of the body of the instrument.

2. A bridge for an instrument of the viol class comprising a substantially flat-sided and upright standard, supports for the standard at either end thereof and occupying substantially the plane of the standard, and pivot means connecting the supports to the standard, each support having an elongated foot portion extending in the plane of the standard, the pivot means for each support comprising a journal portion integral with the foot portion carried above and in the plane of the support and rounded over an arc that is more than half round but less than full circle, and at the base of the standard a bearing portion complementing the journal portion rounded over an arc that is more than half round but less than full circle and opened at the base of the standard, said bearing portion rotatably mounting said journal portion.

3. A bridge for an instrument of the viol class comprising a substantially upright standard, supports for the standard at either end and adjacent the base thereof, and pivot means connecting the supports to the standard, the pivot means for each support comprising a cylindrically curved journal portion curving over an angle that is

greater than 180° and less than 360° and about an axis extending obliquely to the plane of the standard, said journal portion being integral with and carried above the support and in the plane of the standard, and at the base of the standard a cylindrically curved bearing portion complementing the journal portion and curving over an angle that is greater than 180° and less than 360° and about an axis extending obliquely to the plane of support, the bearing portion rotatably mounting the journal portion.
